UNITED STATES PATENT OFFICE

2,648,323

GAS FIRED AIR HEATER

Edward Kent, Detroit, Mich., assignor, by direct and mesne assignments, of twenty-two per cent to Charles E. Wisner, twenty-two per cent to Clarence J. McLeod, and twenty per cent to Carlton F. Brown

Application March 22, 1948, Serial No. 16,291

1. Claim. (Cl. 126—90)

1

This invention relates to an air conditioning system for use in heating a room or rooms of a building and particularly adapted for use in a dwelling, the object being to provide a new character and form of apparatus to be positioned in the room in association with which is a conduit opening to atmosphere at one end and air passes through the apparatus to the space to be heated after the manner as shown and described in my U. S. Patent No. 2,258,682 of October 14, 1941.

In the drawing:

Fig. 1 is a front elevation of my improved heating apparatus.

Fig. 2 is a side elevation thereof.

Fig. 3 is a front elevation with the cover plate removed.

Fig. 4 is a section taken on line 4—4 of Fig. 1.

Fig. 5 is a section taken on line 5—5 of Fig. 3.

Fig. 6 is a section taken on line 6—6 of Fig. 5.

Fig. 7 is a section taken on line 7—7 of Fig. 5.

Fig. 8 is a section taken on line 8—8 of Fig. 5.

Fig. 9 is a section taken on line 9—9 of Fig. 3.

Fig. 10 is a section taken on line 10—10 of Fig. 3.

The invention herein disclosed is comparatively simple and of less cost than the structure shown in my said patent and comprises a frame element 1 rectangular in cross section and having a rear plate 2 and a forward plate 3 in spaced relation as shown in Fig. 4. The bottom plate 4 of the framework is shaped to support an end of the air conduit 5 which preferably opens to atmosphere.

Spaced forwardly from the plate 3 is a plate 6 having a series of vertically spaced horizontal ribs 7 triangular in cross section on its outer face. These ribs 7 are less in length than the distance between the side walls 25 and 26 and are so arranged that heated gases flow back and forth between the ribs transversely of the plate 6 as indicated by the arrows in Fig. 3.

At the bottom and forward side of the plate 6 is a gas burner 8 having a series of apertures 9 through which gas is discharged to flow upwardly and transversely of the forward face of the plate 6 between and around the ends of the triangular members 7 and thence downwardly in the space 10 between the plates 3 and 6 and passes through apertures 11 in the plate 3 and thence upwardly in the passageway 12 at the back of the plate 3 and discharges downwardly through the passage 13 to exhaust pipe 14 as will be understood from Figs. 1 and 9. By means of the conduit 5 air is discharged through the open end 21.

2

Preferably a removable plate 15 is provided on the inner face of the plate 6 which has a series of V shaped elements 7, the apices of which are rounded, and practically in contact with the plate 15 to prevent the burning gases from flowing directly upward. This restricts the rapidity of flow of the burning gases. The plate 15 may be formed of transparent, fire resistant material and has a series of apertures 16 at the lower end to permit air and burned gases to pass upward and around the ends of the triangular members 7 and thence downwardly through the passageway 10 and apertures 11 in the plate 3 and thence upwardly through the passageway 12 as shown in Fig. 5.

The passageway 13 is provided with a conduit 14 open to atmosphere and a plate 20 separates the passageways 13 and 12. The heated air passes upwardly in the passageway 5 to the outlet 21 to the room being heated.

Fuel is discharged to the burner through a conduit 22 as shown in Figs. 1 and 3, and this conduit 22 is provided with apertures 23, and on the conduit is an imperforate ring 24 slidable thereon to vary the area of the apertures and thus permit a greater or less volume of air per unit of time to be introduced into the gas stream flowing in the conduit 22 to the burners.

The apparatus may be made in various size depending upon the area of the space to be heated. A small size is adapted for use in a trailer in which case gas under pressure would be provided in a tank in the trailer.

It is believed obvious from the foregoing description that the features and objects of the invention are attained by the structural arrangement of parts as hereinbefore described.

Having thus briefly described my invention, its utility and mode of operation, what I claim and desire to secure by Letters Patent of the United States is:

An air conditioning system adapted for heating the air in an enclosed space comprising an upright housing of rectangular shape in cross section and comprising front, rear, top, bottom and side walls, a flat upright plate therein engaging said side walls, spaced rearwardly of the front wall thereof, a fuel burner upon the bottom wall of said housing between said front wall and plate and extending across the width of said housing, a series of vertically spaced horizontal ribs mounted upon the front side of said plate and with their outer ends projected towards and terminating adjacent said front wall, said ribs being shorter than the width of said plate with alternate ribs joined to alternate sides of the

housing to provide a circuitous upward passage for the products of combustion adjacent said plate, said housing front wall having a plurality of air inlet slots at its lower end adjacent said burner, a second flat upright plate transversely apertured at its lower end, spaced rearwardly of said first plate and extending across the interior of said housing to define an elongated passage between said plates for the downward flow of said products of combustion, means at the top of said plates communicating said passages, an upright air conduit centrally arranged within said housing between and spaced from said second plate and the rear wall of said housing, said conduit having an outlet extending horizontally over the top of said housing adapted to communicate with said enclosed space, said conduit extending below said housing and having an inlet adapted to communicate with said enclosed space, a pair of spaced upright coplanar plates intermediate said second plate and the rear wall of said housing with their outer upright edges joined to the side walls of said housing and their inner upright edges joined to side wall portions of said conduit, thereby defining second elongated passages for the upward flow of said prod-

ucts of combustion adjacent said second plate, and additional spaced passages for the downward flow of said products of combustion adjacent the rear wall of said housing, means joining the upper portions of the latter passages and said second elongated passages, and an exhaust pipe joined to the rear wall of said housing in communication with the lower ends of said last passages, and with its other end adapted for communication with the outside atmosphere.

10

EDWARD KENT.
